UNITED STATES PATENT OFFICE.

ADOLPH H. LICHTER, OF TOLEDO, OHIO, ASSIGNOR TO THE WILLYS-OVERLAND COMPANY, OF TOLEDO, OHIO, A CORPORATION OF OHIO.

SPRING UPHOLSTERED CUSHION.

Application filed June 17, 1920. Serial No. 389,561.

To all whom it may concern:

Be it known that I, ADOLPH H. LICHTER, a citizen of the United States, and a resident of Toledo, in the county of Lucas and State of Ohio, have made an Invention Appertaining to Spring Upholstered Cushions; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention has for its object to provide an upholstered unit which can be readily placed in position with or relative to other units and readily removed therefrom. It particularly has for its object to provide in 20 an upholstered unit a spring frame for upholstering cushions, which may be readily formed, which has a supporting rigid part and wherein the shape of the upholstered part may be maintained and the cushion, as 25 a whole, will maintain its designed shape notwithstanding the ordinary use to which the cushion is subjected. Also by my invention is provided a means for readily attaching, or connecting, the upholstering part 30 to the cushion frame.

The invention has for its object other features and advantages which will appear from the following description and upon the examination of the drawings.

35 The invention may be contained in cushioned structures of different forms. To illustrate a practical application of the invention, I have selected a cushion containing the invention and shall describe it herein-after. The structure selected is illustrated in the accompanying drawing in which—

Figure I is an end view of the cushion frame.

Fig. II is a fragmentary front elevation 45 of the cushion frame shown in Fig. I, with the upholstery and padding removed;

Figs. III and IV are details showing the connection of the brace rods to the frame;

Fig. V is a detail of the base frame; and

Fig. VI is a view showing a modified arrangement of the braces.

1, in Fig. I, denotes the springs that are supported on a rigid frame 2. They are connected thereto by any suitable means such as by striking up tongues that may be

clinched down around the lower coils or turns of the springs. The frame 2 is formed of a plurality of cross-bars 3 having raised central portions 4 that form ribs for purposes of making the cross members or bars 3 strong and rigid. The cross bars 3 are connected together by means of strips 5 of metal. The cross bars 3 may be secured to the strips 5 by spot-welding or by any other suitable means. The ends of the bars 3 and the strips 5 are bound together by the bottom edge wire or rod 6 that extends all around the frame of the cushion. The ends of the bars and strips are rolled over the rod or heavy wire 6 which affords a means for readily clinching the bars and strips in position and a means for readily connecting the bars and strips to the marginal wire 6.

The cushion shown in the drawing is particularly designed for the back of an automobile upholstered seat. The top side or edge of the cushion is provided with a bar or large wire 8 that extends the length of the cushion and its ends 9 are turned inward near the ends of the cushion. A plurality 75 of wires 14 extend from the upper strip 5 to the wire 8. They are secured by means of clips 15 to the wire 8 and by means of the strips 16 to the strips 5. The strips 16 are secured to the strips 5 by means of suitable rivets or by spot-welding. The strips 16 and the clips 15 form pivotal connections for the stay wires 14. When, then, the upper edge 80 of the cushion is pressed, the wires 14 extending from the wire 8 to the frame operate 90 to push the wire 8 upwards and outwards and carry with it the cushioning material and thus prevent the cushioning material from sagging between the base marginal wire 6 and the top marginal wire 17 which 95 extends all the way around the top of the cushion. In this operation, the centers of the springs to which the wire 9, is connected will, of course, be pushed outwards, that is, upwards.

100 The top marginal wire 17 is secured to the outside spiral springs 1 by means of suitable clips. The top marginal wire 17 is connected to the rigid part of the frame by means of stay wires 18 and 19 which are connected to the strips 5 by means of the strips 16 and 20. The stay wires as shown in the form 105 illustrated in Fig. III cross each other, that is, the stay wires 19 are connected by means of the strips 16 and 20 to the upper strip 5 110

while the stay wires 18 are connected by means of the strips 20 to the lower strip 5. When, therefore, the marginal wire 17 is pressed, the stay wires 18 and 19 will operate 5 to spread the side portions of the marginal wire and thus prevent any of the upholstering cover from becoming so loose that any portion thereof will sag. Brace wire 30 is connected to lower strip 5 and marginal 10 wire 17 by suitable fastening means, such as used for stay wire 14, and is for the purpose of preventing the deformation of the marginal wire 17 from being directly communicated to the continuation of marginal 15 wire 17 that functions in the other half of the cushion (not shown). There are preferably only two stay wires 30 located in the middle of the cushion. The tendency of the stay wires is to keep the upholstering portion neatly stretched over the top of the cushion notwithstanding any compression that may occur locally on the cushion.

If desired, the stay wires may extend from the strips 5 located nearest the sides of the 25 marginal wire 17, that is to say, the wires 28 may be connected by means of the strips 20 to a strip 5 and the wires 29 may be connected to a strip 5 as shown in Fig. VI. In other words, the points of connection of the 30 ends of the wires 18 and 19 may be reversed and their ends may be connected to the ends of the strip 20 reverse to that shown in Fig. 2 of the drawings. In this way, the spreading effect of the wires 18 and 19 will be increased 35 so as to stretch the cushion cover when any portion thereof is compressed. This change in connection of the stay wires 18 and 19 is shown in Fig. VI.

I claim:

- 40 1. In a back cushion, a base, a plurality of springs connected to said base, a top marginal wire extending around the springs, a pair of sets of stay wires connected to the base at points intermediate the sides thereof and to points along the marginal wire that correspond to the top and bottom of the cushion, the stay wires of each set lying in the same plane, each set being connected to a side of the marginal wire opposed to the 45 side of the marginal wire connected to the other set and adapted for spreading the sides of the marginal wire and the upholstery of the cushion, when said cushion is compressed.
- 50 2. In a cushion, a base, a plurality of springs connected to said base, a top marginal wire extending around the springs, two sets of diagonal stay wires connected to the base at points intermediate the sides thereof and to points intermediate the ends of those portions of the top marginal wire which correspond to the sides of the cushion, each set of diagonal stay wires being connected to an opposite side of said top marginal wire for spreading the marginal wire 55

and the top of the cushion, when the cushion is compressed.

3. In a cushion, a frame having a rigid part, a top marginal wire extending around the edges of the cushion and having stay wires pivoted thereto for expanding the area of the marginal wire, springs secured to the fixed part and located within the top marginal wire, a second wire connected to two of the springs of each end of the cushion 70 and extending along the side of the cushion and located between the top marginal wire and the rigid part of the frame and having stay wires for forcing the last named wire 75 outwards when the portions of the cushion 80 are compressed.

4. In a spring cushion, a frame having a base portion, a set of springs mounted thereon, a top border wire secured to said springs, upholstery covering said springs and border 85 wire, said border wire being braced by cross diagonal stay wires attached thereto and to the supporting frame, certain of said stay wires being connected to one side of said border wire and certain others being connected to the opposite side of said border wire, said wires being attached to the base portion intermediate its sides, an intermediate border wire adapted to support said upholstery, and means extending diagonally 90 from said intermediate border wire to said base portion and cooperating with said intermediate border wire to prevent sagging of said upholstery when the springs are compressed. 95

5. In a spring cushion, a border wire, a base, a series of springs thereon, upholstery covering said springs, and means attached to the base at points spaced from the side edges thereof and to opposite sides of the 100 border wire at points intermediate the ends thereof and adapted to prevent sagging of said upholstery.

6. In a spring cushion, a base, a set of springs supported thereon, a top border wire 110 carried thereby for defining the outline of said cushion, upholstery covering said springs and border wire, and a plurality of cross stays attached to said base and to said border wire and extending up from points 115 intermediate the sides of said base to points intermediate the ends of said border wire certain of said stays being connected to one side of said border wire and certain others being connected to the opposite side of said border wire whereby said upholstery is maintained taut when the springs are compressed. 120

7. In a spring cushion, a base, a series of springs thereon, upholstery covering said 125 springs, and means extending longitudinally along one side of the cushion and connected to certain of said springs intermediate their ends and means connected to the first mentioned means and to said base coating with 130

the first mentioned means for counteracting the tendency of the upholstery to sag when the springs are compressed.

8. In a spring cushion, a border member, 5 a base, a series of springs thereon, upholstery covering said springs, and means attached to the base intermediate the sides thereof and to opposite sides of the border

member at points intermediate the ends thereof, adapted to spread said border member when the springs are compressed, whereby to prevent sagging of the upholstery. 10

In testimony whereof, I have hereunto signed my name to this specification.

ADOLPH H. LICHTER.
